MICROWAVE SLOT COUPLING

John E. Gibson, Washington, D. C.

Application October 25, 1945, Serial No. 624,619

5 Claims. (Cl. 178—44)

(Granted under Title 35, U. S. Code (1952),
sec. 266)

1

This invention relates in general to the transfer of electrical energy and in particular to an arrangement for the coupling of high frequency energy between components of a microwave system or between two such systems.

In the usual high frequency system, such as is encountered in the field of radio echo ranging and related activities, the problem of transferring energy from one component to another must frequently be solved by means which take into account the fact that even the smallest circuit element, if possessed of any power-handling ability, has physical dimensions one or more of which constitutes an appreciable fraction of a wavelength. This electrical-length property denies a solution by ordinary direct current or low-frequency methods, since circuits at very short wavelengths rarely satisfy the conditions which warrant the assumption of an infinite characteristic electromagnetic velocity. Just as the need for the satisfaction of these conditions or for methods particularly adapted to the problems presented dictated the adoption of concentric transmission lines and waveguides, so also did they dictate the adoption of energy coupling methods which bear little physical resemblance to D. C. or low-frequency coupling methods.

It is an object of this invention to provide a means of transferring energy at frequencies in the frequency spectrum above 1000 megacycles per second.

It is another object of this invention to provide an efficient, convenient means of transferring energy from one transmission line to a second transmission line.

It is another object of this invention to provide a coupling-slot means of transferring energy from one system to another which permits the efficiency of transfer to be maintained at its optimum value over a wide range of frequencies by simple mechanical tuning.

Other objects and features of this invention will become apparent upon a careful consideration of the following detailed description when taken together with the accompanying drawings in which:

Fig. 1 is a diagram illustrating certain of the principles upon which this invention is based;

Fig. 2 is an elevational view of a high frequency generator utilizing one embodiment of this invention;

Fig. 3 is an end view of the embodiment of Fig. 2 partially in cross-section looking in the direction of arrows 3—3 of Fig. 2.

2

Fig. 4 is a detailed view of the embodiment of this invention illustrated in Fig. 2.

Reference is now had in particular to Fig. 1 wherein there is shown a diagram illustrating certain of the principles upon which the teachings of this invention are based. Surface 1 represents a portion of one surface of a conducting sheet serving to separate, and to act as conducting boundary surfaces for, regions in which electromagnetic fields may be caused to exist. At frequencies corresponding to centimeter or decimeter wavelengths the depth of penetration of the electromagnetic fields into the surfaces of the conducting sheet is so small that essentially no mutual interaction between the electromagnetic fields is possible even though the conducting sheet serves as a common boundary conductor. Consider an electromagnetic field to be generated, by means not shown, in the region bounded by surface 1 with such an orientation as to tend to produce a current flow on surface 1 everywhere parallel to bounding edges 2 and 3. An aperture 4 having a width w which is a fractional part of a quarter wavelength and a length l equal to one half wavelength is cut in the conducting sheet with its long dimension lying perpendicular to the direction in which current tends to flow on surface 1. Such an aperture or slot has many properties similar to those of a half-wave two-wire Lecher frame. Considered independently of any shunt impedances provided by any circuit system of which the conducting sheet is a part, the impedance across the slot measured between opposite points on the slot edges having a length l is resistive and varies from a high value at the slot midpoint to zero at the ends. Taken similarly, the impedances across the slot for values of l representing more or less than one half wavelength varies between the midpoint and the ends in a manner similar to that obtained with a Lecher frame of corresponding length. Since the slot is common to both surfaces of the conducting sheet, it represents a common impedance between any circuit system of which surface 1 is a part and any circuit system of which the opposite surface is a part. Thus, the provision of an electromagnetic field tending to induce a current in surface 1 parallel to edges 2 and 3 will tend to cause a current flow in the opposite surface and thereby a current flow in any circuit system of which this surface is a part. Further, the provision of an electromagnetic field tending to induce a current in surface 1 not parallel to edges 2 and 3 but of an orientation such that aperture 4 has at least

a component of its length dimension perpendicular to the direction of induced current flow will also cause a current flow in the opposite surface. In general, the greater the component perpendicular to the direction of induced current, the more effective is the production of a current in the opposite surface. The manner in which these phenomena are utilized for the transfer of energy will be described more fully in connection with a practical embodiment of this invention.

In Fig. 2 is shown such a practical embodiment in the form of a generator of oscillations in the 2400 to 3400 megacycle per-second band of the frequency spectrum. This generator, comprising two lighthouse-type triode vacuum tubes particularly designed for high frequency work and a plurality of concentric cylindrical members as resonant sections, operates in a manner described in my co-pending application entitled "Ultra-High Frequency Oscillator," Serial No. 624,618, filed October 25, 1945. The two tubes, one of which is indicated at 20, are generally disposed in face-to-face relationship at opposite ends of the oscillator and are separated by the cylindrical members which constitute the resonant section. Furthermore, the tubes operate with a phase difference of 180 degrees so that the generator functions in a manner somewhat analogous to the manner in which a conventional push-pull tuned-plate tuned-cathode low frequency oscillator functions. While this analogy is limited by the inadequacy of ordinary circuit theory at extremely high frequencies, it does extend to the requirement for an energy transfer from the plate-grid resonant section to the cathode-grid resonant section in order to provide the feedback coupling to support self-oscillation.

In Fig. 2 a section has been cut away to expose the disposition of the components comprising one end of the oscillator. The unexposed end is essentially identical and includes the other triode tube. In general, telescopic cylinder 5 represents the inner conductor and telescopic cylinder 6 the outer conductor of a three half wavelength resonant concentric transmission line. This line constitutes the plate-grid resonant section of the oscillator and in the mode in which the generator is operated is characterized by the location of a voltage node and current loop at the generator midpoint defined by a plane 3-3 through the generator transverse to its longitudinal axis. Likewise, and again in general, telescopic cylinder 6 represents the inner conductor and telescopic cylinder 7 the outer conductor of a portion of a five half wavelength resonant concentric transmission line. This line constitutes the cathode-grid resonant section and is likewise characterized by the location of a voltage node and current loop at the generator midpoint. Since oscillation requires that anode and cathode voltages with respect to grid be essentially in phase, the difference in electrical length of an odd full wavelength between the two sections establishes a phase difference of essentially 180 degrees for the currents on the outer and inner surfaces of cylinder 6 at the midpoint of the generator. There is no coupling between the two resonant sections merely by virtue of their common use of cylinder 6 since, at the frequencies under consideration, current flow is substantially a surface phenomenon and the thickness of cylinder 6 is very large in comparison to the depth of current penetration. The resonant transmission-line sections operate in the usual TEM mode

of coaxial transmission lines so that the electrical field is radial, the magnetic field is circumferential, and current flows in a direction parallel to the longitudinal axis of the generator.

5 Telescopic cylinder 5 comprises in part a central element 5', telescopic cylinder 6 a central element 6', and telescopic cylinder 7 a central element 7', all of such central elements being held in a fixed position relative to chassis 8. The 10 movable elements (5, 6, and 7) of the three cylinders provide the means by which the physical lengths of the resonant sections may be changed and thus the generator tuned to a desired frequency within its band of operation.

15 At the generator midpoint there is cut into central element 6' a circumferential slot corresponding to aperture 4 of Fig. 1. This slot, which has been given the reference numeral 9, is best illustrated in Fig. 4 which is a diagram of the mid-section of element 6'. It will be seen that this slot is disposed with its length transverse to the direction of current flow along the inner and outer surfaces of element 6' and that it has been provided with a pair of shoulders 10 and 11 not present in the case of aperture 4 of Fig. 1. Shoulders 10 and 11 comprise a circular conducting disc fixed to element 6' across aperture 9 which disc has had its midsection removed to coincide with the interception of the aperture 20 and represents a part of the means by which, according to the teachings of this invention, the electrical length of a slot of fixed physical length, such as slot 9, is maintained at an optimum value for the particular frequency to which the generator may be tuned. In the same way in which a lumped capacitance across the midpoint of a half-wave Lecher frame shorted at both ends can be utilized to maintain the electrical length while a reduction is made in its physical length, the 25 lumped capacitance across the midpoint of slot 9 serves to extend the equivalent electrical length beyond that provided by mere physical length.

Reference is now had to Fig. 3 which represents an end view of the generator of Fig. 2 in which a section has been cut away to reveal the disposition of coupling slot 9, associated shoulder 10 (shoulder 11 being hidden in this view), and variable plate 12. It will be seen that the total capacitance across the slot at its midpoint consists, not only of the fixed capacitance between shoulders 10 and 11, but also of the series sum of the capacitance between shoulder 10 and the portion of plate 12 immediately adjacent thereto and the capacitance between shoulder 11 and the portion of plate 12 adjacent to it. Thus, movement of plate 12 may be utilized to vary this total capacitance and thereby to vary the electrical length of the slot to the optimum value for the transfer of energy between the two resonant sections. Threaded adjusting member 13 is supported from outer cylinder element 7' by means of boss 14. Plate 12 is preferably surfaced with mica to prevent the short-circuiting of shoulders 10 and 11 when plate 12 is adjusted to a position 30 providing little separation.

Since slot 9 is disposed in a transverse sense to the longitudinal flow of alternating current along the inner surface of element 6', a condition exists, such as was described in connection with Fig. 1, in which slot 9 constitutes a common impedance between the plate-grid resonant section and the cathode-grid resonant section and provides for coupling by virtue of the mutual impedance which exists. Thus, electromagnetic energy existing in the plate-grid resonant section

is accompanied by a current flow on the inner surface of element 6' at the midpoint tending to be everywhere parallel to the longitudinal axis of the oscillator, and the flow of this current in the vicinity of the slot is impeded by a total impedance consisting of the slot impedance in shunt with the effective impedance of the cathode-grid resonant section as seen at the slot looking from the plate-grid resonant section into the cathode-grid section. Therefore, if, for example, optimum tuning of the cathode-grid resonant section is represented by the resonance condition, the effective impedance of the cathode-grid section as measured from terminals at the slot is essentially resistive, and if the slot is tuned to resonance, that is, tuned to represent resistive impedance when taken by itself, the total impedance across the slot to current flowing on the inner surface of element 6' in the vicinity of the slot is resistive and has a magnitude equal to the parallel sum of the slot impedance and the cathode-grid section effective impedance. In this case, at points corresponding to the oscillator midpoint, the directions of the current flows on the outer and inner surfaces of element 6' corresponding to excitation of the plate-grid and cathode-grid sections each as a whole are opposite at all times during the cycle. Also, in this case, the current flow around the ends of the slot, corresponding to the excitation of the slot itself, occurs with a quarter cycle phase difference with respect to the current flow in the resonant sections as a whole. The degree of coupling provided by the slot is dependent in part upon the proportion of the circumference of element 6' occupied by the slot, and varies from negligible values for slots of infinitesimal length to large values where the slot length is made to approach the circumference of element 6'. For the same tuning conditions with respect to resonance, increasing the slot length decreases the effective impedances of the plate-grid and cathode-grid resonant sections as measured from opposite points across the slot. If the most desirable phase of excitation of the cathode-grid section with respect to the plate-grid section differs somewhat from that corresponding to direct opposition of the current flows on the outer and inner surfaces of element 6', the slot may be detuned from resonance by an amount and in a sense such as to obtain a reactive slot impedance which, in combination with the effective impedances of the plate-grid and cathode-grid sections yields the desired phase of excitation in accordance with the principles underlying the operation of the more familiar circuit networks.

Thus, it is seen that the application of the teachings of this invention permits the provision of a slot coupling means affording a desired degree of coupling, and permitting the adjustment of the phase of excitation to an optimum value at any frequency in a wide portion of the frequency spectrum.

Although a particular slot shape has been described, this particularity has been employed, not to establish limits in configuration, but to facilitate description of the principles of operation. Actually, the dimensions of the aperture and the shape of the aperture may vary according to the requirements of a particular situation. The length dimension of one-half wave length is a special case, the optimum length under other conditions may be more or less than one-half wavelength. The same basic effect is obtainable with apertures in shapes other than simple slots

without exceeding the limits of this invention. While reference has been made herein to a simple slot disposed with its length dimension perpendicular to the direction of current flow, it should be understood that this disposition is only the most readily explainable and is only a special case of an aperture having a component of length disposed transversely to the direction of current flow. The aperture may be disposed with its length dimension at any angle other than along the direction of current flow (slot width being taken as negligible). The degree of coupling depends upon the angle of the slot and varies from zero for the slot parallel to current flow to a maximum value for the transverse position. In the cylindrical generator application, this feature affords a variable coupling possibility separate from the variation of coupling possible through changes in the proportion of cylinder circumference occupied. To those versed in the art this obviously represents a convenient means of varying the coupling in certain suitable arrangements such as waveguide apparatus.

Again, it should be understood that, although the coupling slot which has been described is a preferred embodiment of this invention, it by no means establishes the boundary application. For example, a similar coupling slot, similarly oriented, but inserted in outside cylinder 7 at the generator midpoint could be used to transfer energy from the cathode-grid resonant section to a waveguide so as to excite the waveguide in a suitable mode to act as a transmission line between the generator and an external load. Further, it will be seen that other applications, differing in physical arrangements but the same in principles, may be made to advantage. As an example of this, a resonant circuit may consist of parallel plane conducting walls which may contain an aperture or apertures which function to transfer energy in the manner explained. For the purposes of this disclosure, such an arrangement is defined, in the same sense that the plate-grid and cathode-grid sections of the generator of Fig. 2 are defined, as a wall enclosed component part.

Since certain further changes may be made in the foregoing construction and different embodiments may be made without departing from the scope thereof, it is intended that all matter shown in the accompanying drawings or set forth in the accompanying specification shall be interpreted as illustrative and not in a limiting sense.

The invention described herein may be manufactured and used by or for the Government of the United States of America for government purposes without the payment of any royalty thereon or therefor.

What is claimed is:

- 60 1. In combination, a plurality of conducting wall members arranged to constitute a plurality of nested energy containing sections of which at least two have a common wall member, said two sections having said common wall member being so oriented that the directions of current flow along the surfaces of said common wall member in said two sections are parallel, a means coupling energy from one of said two sections into the other of said two sections comprising an aperture cut in said common wall member, and a lumped variable capacitance across said aperture at its physical midpoint, said aperture being, in width, a fractional part of a wavelength at the frequency of said energy and, in length, less than a half wavelength at said frequency, said aper-
- 65
- 70
- 75

ture also being disposed in said common wall member with its length dimension transverse to said directions of current flow, said lumped variable capacitance being provided by a pair of coaxial circular discs, one of which is fixed on said common wall member across said aperture with its axis perpendicular to the axis of said common wall member and which has its mid-section removed to coincide with the interception of said aperture and the other of which is movable with respect to said fixed disc, said movability providing a range of variable reactance such that the electrical length of said aperture may be made to represent substantially a half wavelength at said frequency.

2. In combination, a plurality of conducting wall members arranged to constitute a plurality of nested energy containing sections of which at least two have a common wall member, said two sections having said common wall member being so oriented that the directions of current flow along the surfaces of said common wall member in said two sections are parallel, a means coupling energy from one of said two sections into the other of said two sections comprising a slot cut in said common wall member transverse to said directions of current flow, said slot being, in width a fractional part of a wavelength at the frequency of said energy and, in length less than a half wavelength at said frequency, a pair of conducting parallel plates, one of said plates being fixed on said common wall member at the physical midpoint of said slot, said plates having a width greater than that of said slot and a length less than that of said slot, said one plate having its midsection removed to form an aperture coincident with but of smaller width than said slot, and means for moving said other plate axially toward and away from said first plate.

3. In combination, a plurality of conducting wall members arranged to constitute a plurality of nested energy containing sections of which at least two have a common wall member, said two sections having said common wall member being so oriented that the directions of current flow along the surfaces of said common wall member in said two sections are parallel, a means coupling energy from one of said two sections into the other of said two sections comprising a slot cut in said common wall member transverse to said directions of current flow, said slot being, in width a fractional part of a wavelength at the frequency of said energy and, in length less than a half wavelength at said frequency, a pair of conducting coaxial parallel discs, one of said discs being fixed on said common wall member at the physical midpoint of said slot, said discs having a diameter greater than the slot width and less than the

slot length, said one disc having its midsection removed to form an aperture coincident with but of smaller width than that of said slot, and means for moving said other disc axially toward and away from said one disc.

4. In a cavity type oscillator having concentric cavities forming a wall member common to two cavities on which the current in each of the two cavities is parallel, coupling means between 10 said two cavities providing the optimum feed-back for supporting oscillations comprising, an elongated slot in said common wall member having a length less than a half wavelength at the frequency of said oscillations, said slot being positioned 15 transverse to the flow of said currents, a pair of conducting parallel plates, one of said plates being fixed on said common wall member at the physical midpoint of said slot, said plates having a width greater than that of said slot and a length less than that of said slot, said one plate having its midsection removed to form an aperture coincident with but of smaller width than said slot, and means for moving said other plate axially toward and away from said first plate.
- 25 5. In a cavity type oscillator having concentric cavities forming a wall member common to two cavities on which the current in each of the two cavities is parallel, coupling means between said two cavities providing the optimum feedback for 30 supporting oscillations comprising, an elongated slot in said common wall member having a length less than a half wavelength at the frequency of said oscillations, said slot being positioned transverse to the flow of said currents, a pair of conducting coaxial parallel discs, one of said discs being fixed on said common wall member at the physical midpoint of said slot, said discs having a diameter greater than the slot width and less than the slot length, said one disc having its mid-section removed to form an aperture coincident with but of smaller width than that of said slot, and means for moving said other disc axially toward and away from said one disc.
